Atty.*

UNITED STATES PATENT OFFICE.

EDWARD JULIUS LONN, OF LAPORTE, INDIANA, ASSIGNOR TO GREAT WESTERN
MANUFACTURING CO., OF LAPORTE, INDIANA, A CORPORATION OF INDIANA.

DESIGN FOR A BICYCLE MUD-GUARD.

56,288.

Specification for Design. Patented Sept. 14, 1920.

Application filed January 29, 1920. Serial No. 354,941. Term of patent 14 years.

To all whom it may concern:

Be it known that I, EDWARD JULIUS LONN, a citizen of the United States, residing at Laporte, in the county of Laporte and State of Indiana, have invented a new, original, and ornamental Design for Bicycle Mud-Guards, of which the following is a specification, reference being had to the accompanying drawing, forming part hereof.

The figure is a view in perspective of a bicycle mud guard, showing my new design.

I claim:

The ornamental design for a bicycle mud guard, as shown.

EDWARD JULIUS LONN.
